UNITED STATES PATENT OFFICE.

EDWARD J. FOWLER, OF REDWOOD CITY, CALIFORNIA, ASSIGNOR TO GENERAL CHEMICAL COMPANY, OF NEW YORK, N. Y., A CORPORATION OF NEW YORK.

ROASTING-FURNACE SHAFT.

1,278,129.

Specification of Letters Patent. Patented Sept. 10, 1918.

Application filed July 3, 1915. Serial No. 37,810.

To all whom it may concern:

Be it known that I, EDWARD J. FOWLER, a citizen of the United States, and a resident of Redwood City, county of San Mateo, and State of California, have invented certain new and useful Improvements in Roasting-Furnace Shafts, of which the following, taken in connection with the accompanying drawings, is a specification.

10 My invention relates to furnaces, especially such as are used for roasting ores, and such as are provided with superposed stationary hearths upon which the ore is stirred and distributed by rakes or plows affixed to rotating arms, said arms being in turn affixed to and rotatable with a central vertical shaft which extends through central apertures in the hearths and is rotated by any suitable mechanism.

20 More particularly my invention relates to the central, rotatable shafts of such furnaces, of the type in which longitudinal passages are provided for conducting a cooling medium to and from the rabble arms through a plurality of longitudinally spaced and angularly disposed sets of rabble arm inlet and outlet ports or apertures, and an object of my invention is to produce a shaft in which the passages are provided by partitioning the outer shell of the shaft longitudinally, the partitioning means extending between and separating the inlet and outlet ports of each of said sets. Another object of my invention is to produce a hollow shaft having rabble arm outlet and inlet ports and having partitioning means extending between and separating the said ports, said partitioning means dividing the shaft into unequal cross-sectional portions. Other objects of my invention will be pointed out or will otherwise appear in the following description of an embodiment of my invention in which—

Figure 1 is a longitudinal sectional view on the line 1—1 of Fig. 2,

Fig. 2 is a cross-section on the line 2—2 of Fig. 1, and

Fig. 3 is a cross-section on the line 3—3 of Fig. 1.

The shaft illustrated is composed of longitudinal articulating sections of which two only are shown in Fig. 1. Each section consists of an outer cylindrical shell 4, provided with rabble arm inlet ports 5 and rabble arm outlet ports 6, the adjacent ports 5, 6

constituting a set through which a cooling medium is conducted to and from each rabble arm 7, and the set or sets of ports in one horizontal plane being angularly disposed, as shown at right angles, with reference to the set or sets in a plane longitudinally spaced from the first mentioned plane. The rabble arms are, of course, provided with the usual channels for the cooling medium and are secured to the shaft in any suitable and well-known manner. The rabble arms of one horizontal plane are adapted to move material on one of the furnace hearths while the rabble arms thereabove and extending at right angles to the first mentioned arms are adapted to move material on the hearth immediately above the first mentioned hearth.

Secured within the shafts, and dividing it into two longitudinal passages 8 and 9, is a partition or vane 10 the peripheral edges of which partition extend between the ports 5, 6 of each set and separates them so that each port 5 is in communication with said longitudinal passage 8 and each port 6 is in communication with said passage 9. The sets of ports are angularly disposed and the partition 8 is curved in the form of a spiral. The intermediate portion of the spiral partition is curved away from the straight diametrically extending line of the edge portions thereof so that a bulged or concavo-convex central part 11 is formed; thus the partition is made to divide the shaft into unequal cross-sectional portions, the portion 8 being of less cross-sectional area than the portion 9.

In the operation of the furnace a suitable cooling medium is conducted into the spiral shaft passage 8 from which it passes through the various inlet ports 5 into the arms, after traversing which it passes through the outlet ports 6 and enters the spiral shaft passage 9 and finally escapes from said passage at the end thereof. In this way the cooling medium is continuously circulated, the structural means for accomplishing this circulation, a single partition, being of the simplest kind and possessing many advantages of construction and operation. The curved form of this partition which can be cast integrally with the shell 4 or be formed separately and then secured to the said shell, is of great practical value because, among other advantages, it enables the construc-

tional elements to withstand the stresses of unequal expansion without danger of shearing. The bulged part 11 contributes to this end and in addition serves to provide a 5 larger passage for the cooling medium after it has been heated and expanded than before it has been heated, thus desirably insuring a substantially constant velocity of the medium in the shaft passages.

10 I claim:

1. A hollow shaft comprising an outer shell provided with a plurality of longitudinally spaced and angularly disposed sets of rabble arm inlet and outlet ports, and a 15 single longitudinal non-diametral partition, dividing the shell into two chambers, common to all of said sets and extending between and separating their inlet and outlet ports.

2. A hollow shaft comprising an outer shell provided with a plurality of longitudinally spaced and angularly disposed sets of rabble arm inlet and outlet ports, and a longitudinal partition of spiral form extending between and separating the inlet and outlet ports of each set.

3. A hollow shaft comprising an outer shell provided with sets of rabble arm inlet and outlet ports, and a single partition 30 lengthwise of the shaft dividing the same into unequal cross-sectional portions, said partition being common to and extending between and separating the inlet and outlet ports of each set.

35 4. A hollow shaft comprising an outer shell provided with rabble arm inlet and outlet ports, and a longitudinal partition extending between and separating said inlet and outlet ports, said partition being of spiral form and having a concavo-convex central portion.

5. In a hollow roasting furnace shaft provided with peripheral rabble arm apertures, a single substantially longitudinal partition 45 in the shaft, one edge of said partition dividing an arm aperture, and the partition itself dividing the shaft into two substantially longitudinal but unequal compartments.

6. In a hollow roasting furnace shaft having peripheral apertures adapted to establish connection with hollow rabble arms, a single longitudinal non-diametral vane dividing said shaft into two compartments for the introduction and for the discharge of a 55 cooling medium, the peripheral edges of said vane forming at the said apertures, partitions dividing said apertures into separate openings.

7. In a hollow roasting furnace shaft having apertures adapted to establish connection with hollow rabble arms, a single longitudinal vane dividing said shaft into two separate compartments for the introduction and for the discharge of a cooling medium, 65 the rabble arms and the apertures therefor on alternate hearths being all in the same plane and at right angles to the arms and apertures on the remaining or intermediate hearths, the peripheral edges of said vane 70 intersecting all the apertures and forming at the said apertures partitions dividing said apertures into separate openings.

8. A hollow shaft comprising an outer shell provided with a plurality of longitudinally spaced sets of rabble arm inlet and outlet ports, the ports of a given set being angularly disposed in the same horizontal plane, and a single non-diametral longitudinal partition therein dividing the shaft into 80 two separate compartments, an edge of said partition being common to and extending between and separating the ports of each and all of said sets.

9. A hollow shaft comprising an outer 85 shell provided with a plurality of longitudinally spaced and angularly disposed sets of rabble arm inlet and outlet ports and a longitudinally twisted partition extending between and separating the inlet and outlet 90 ports of each set.

In witness whereof I have hereunto set my hand in the presence of two subscribing witnesses.

EDWARD J. FOWLER.
